UNITED STATES PATENT OFFICE.

JENNIE E. FLESHER, OF NEW YORK, N. Y.

DESIGN FOR A DRESSMAKER'S SQUARE.

SPECIFICATION forming part of Design No. 22,248, dated February 28, 1893.

Application filed January 3, 1893. Serial No. 457,164. Term of patent 14 years.

To all whom it may concern:

Be it known that I, JENNIE E. FLESHER, of New York, in the county and State of New York, have invented and produced a new and useful Design for Dressmakers' Squares; and I do hereby declare that the following is a full and exact description thereof, reference being had to the accompanying drawing, and to the letters of reference marked thereon, making a part of this specification.

The drawing presents a full side view of a dressmaker's drafting square embodying my design.

The leading feature of my design consists more particularly in the form given to the longer arm of the square.

A is the longer arm of the square and B the shorter arm, the latter being of the usual form. The inner edge or the longer arm is shaped on a compound curved line made up

of suitable curves as follows: From the point *a* to the point *b* the edge is concave, while from *b* to *c* it is nearly convex, and from *c* to *e* convex again. The body of the longer arm A has a curved slot C' as shown, the sides *f* ²⁵ and *g* of said slot being curved so that said slot is wider at one end than at the other, forming practically a tapering slot with curved sides.

I claim as my invention—

The design for a dressmaker's drafting square, substantially as shown and described.

In testimony whereof I have signed my name to this specification in the presence of two subscribing witnesses.

JENNIE E. FLESHER.
